UNITED STATES PATENT OFFICE.

ALFRED E. HYLAND, OF KEESEVILLE, NEW YORK.

CORK-EXTRACTOR AND CAP-REMOVER TOOL.

Application filed February 4, 1928. Serial No. 251,919.

The object of this invention is to provide a simple tool which will be efficient in either removing a metal cap from a bottle or extracting a cork from a bottle, as more fully 5 hereinafter set forth.

In the drawing—

Fig. 1 is a perspective view of the tool complete;

Fig. 2 is a vertical sectional view showing 10 the device in use as a cork-extractor.

In forming my device, I take a piece of steel wire and bend it about midway its length to form a ring 5 open at one side and provided at its closed side with a peened lip 15 6 which forms a part of the cap-remover.

The two end-portions of the wire are extended outwardly away from the ring to form cork-extracting fingers 7, each of which is sharpened toward its point and is provided 20 with a serrated or toothed inner face. These fingers 7 tend to spring apart. The fingers are bent slightly outwardly, away from the ring 5, to form a neck portion 8, and on this neck portion a closed wire loop 9 is arranged 25 to loosely slide, being confined to the neck by the bend in the fingers 7 on the one hand and the ring on the other hand. The two sharpened fingers 7 are housed in the curled edges 10 of a plate 11. The curled edges 10 30 form tubes into which the fingers 7 are pushed endwisely. The far ends of the tubes 10 are closed and, for strengthening purposes, the outer end of the plate 11 is provided with a bead 13. This housing plate 11 together 35 with its tubes 10 not only forms a protector for the sharpened points of the fingers and the serrations on the fingers, but also serves to prevent the fingers springing so far apart as to render the tool inconvenient to handle.

40 The manner of using the device for removing a bottle-cap is obvious; the ring is placed on top of the cap and the peened lip 6 is engaged under the edge of the cap in the usual way; the housing-plate 11 and the fingers 7 45 form a handle when the device is thus used as a cap-remover. When a cork is to be extracted, the housing-plate is removed, i. e., slipped off the ends of the fingers 7; then the fingers 7 are sprung close enough to 50 gether to be jammed down between the cork and the bottle-neck, as shown in Fig. 2; then the loop 9 is pressed down with the fingers so as to prevent the fingers springing apart 55 when the cork is removed. The teeth on the fingers engage opposite sides of the cork and,

by pulling on the ring, the cork will be extracted. The ring serves as a finger-ring in extracting a cork, but, if the cork be so tight in the bottle that the strain is too great for one finger, then a piece of fabric, such 60 as a hankerchief, or a tool or bar may be inserted in the ring. The gravitating loop 9 of course serves to keep the fingers from springing apart after the cork is extracted and thus holds the cork in place between the 65 fingers. With a particularly stubborn cork, increased clamping action by the fingers on the body of the cork may be obtained by forcing the loop 9 downwardly and over the outwardly-spread shoulders on the fingers, as 70 is obvious. It has been found in practice that it will help to loosen the cork and thus make it easier to extract it to slightly twist the ring at the time of pulling. When the cork is pulled, it will remain clamped between the 75 fingers, and, in order to release the cork for reinsertion in the bottle, it is only necessary to loosen the loop 9 to thereby let the fingers spring apart. It has been found in practice that with my device I can pull corks from 80 bottles without spoiling them. It is desirable that one of the tines or fingers, as shown, should be made longer than the other tine or finger, as this facilitates insertion into the cork preparatory to pulling the same. It is 85 also desirable that the rounded shoulders between the narrow portion of the neck 8 and the tines 7 shall be provided with notches 7' so that, when the loose loop 9 is forced down over said shoulders in the extracting of a 90 cork, said loose loop will snap into said notches and thus be held in place during the extracting of the cork and afterward until the loop is manually snapped out of the 95 notches.

What I claim as new is:

A combination tool for the purposes set forth embodying a spring steel wire bent to form an open ring about midway its length the two end-portions extending away from the ring to form fingers and being sharpened and provided with teeth along their inner edges, and a removable shield or housing fitted onto said fingers, said housing embodying a plate and a tube for each of said fingers.

In testimony whereof I hereunto affix my signature.

ALFRED E. HYLAND.
